EXPULSION FUSE

Filed Nov. 17, 1930

INVENTOR:

CYRIL H. THOMAS,

BY: Cheever, Cox & Moore
AT&T

UNITED STATES PATENT OFFICE

CYRIL H. THOMAS, OF FLOSSMOOR, ILLINOIS

EXPULSION FUSE

Application filed November 17, 1930. Serial No. 496,081.

My invention relates in general to electric fuses and has more particular reference to a fuse of the expulsion type in which a fusible element, adapted to melt under predetermined 5 overload conditions in the fuse current, is carried in a housing from which it may be expelled forcibly when the fusible element melts whereby to quickly attenuate and extinguish the arc formed by the fusion of the link and hence to interrupt the current.

It is an important object of my present invention to provide an electric fuse which is reliable and positive in operation and capable of acting promptly to protect an overloaded 15 electrical circuit by quickly and completely extinguishing the electric arc formed by the melting of the fusible element.

Another important object is to provide a fuse formed to utilize the force of the arc 20 itself most effectively to expell or project the arc and the remaining portions of the fusible element in such a manner as to insure the attenuation and extinction of the arc and the consequent rupture of the circuit in which 25 the fuse is arranged to protect the circuit from overloads, the device of my present invention being so constructed that when the fusible element is melted as by an overload, it is expelled in a direction and in a manner 30 quickly to extinguish the arc formed at the point of fusion of the fusible element.

It is a further object of the invention to provide a fuse holder or support of simple, rugged and economic form, which can be 35 manufactured cheaply, which can be readily disconnected from the line for replacement of the fusible element, and which is interchangeable in the spaced mounting elements or clips of standard fuse support mountings 40 at present in general use.

Another important object of my invention is to provide a fuse holder or support of the 45 expulsion type, all parts of which are, when the holder is mounted in its spaced supporting clips or mountings at all times, firmly supported from at least two spaced apart points to insure that the support is firmly mounted against displacement by the explosive forces liberated when the fuse operates or "blows" and wherein after the fuse

has blown no portion capable of forming high resistance leaks remains in series between the spaced fuse clips.

Still another important object is to provide a fuse holder of the class described 55 which is mountable as a unit in a standard high voltage fuse mounting.

Among the other important objects of the invention is to provide a cheap, simple, rugged fuse holder, positive in operation, capable of assembly in standard fuse clips without the use of special adapters or other extraneous devices and having numerous other features of advantage, which will become apparent as the invention is more fully understood 60 from the following description which, 65 taken in connection with the accompanying drawing discloses a preferred embodiment of my invention.

Referring to the drawing:

Figure 1 is a perspective view, partially in section to reveal details of construction, of a fuse and fuse holder embodying my present invention; and

Figure 2 is a vertical cross section taken substantially along the line 2—2 in Figure 1.

To illustrate my invention I have shown on the drawing a fuse holder demountably arranged in operative position between the co-operating blades of the spaced apart clips or fuse holder mountings 11 of a standard fuse mounting or support.

The fuse holder consists of a fuse support comprising a pair of spaced ferrules or caps 15 supported in spaced relation at the opposite ends of a suitable insulating member 13, which may be formed as a tube of relatively heavy insulating material, preferably glass, the caps 15 being provided with sockets 21 into which the ends of the member 13 are secured as by means of bushings 19 or other suitable packing. The caps 15 are preferably cylindrical and provided with a longitudinal bore 23 opening into the bottom of the sockets 21 for the purpose of lightening 85 the support and conserving the material from which the parts 15 are made. The tube 13 and ferrules 15 of course may be made solid, if desired. The ferrules are adapted to engage between the co-operating blades of a 90 95 100

standard fuse mounting, the sides of the caps being formed as at 25 to provide bearing surfaces on opposite sides thereof, whereby the blades of the fuse clips may readily engage and grip the caps whereby to firmly support the fuse holder in position. The member 13 thus acts as a spacing means to insulate and space the ferrules 15 apart.

The support comprising the member 13 and the ferrules 15, also, when assembled between the spaced clips or mounting elements 11 forms a firm base on which the expulsion devices may be securely mounted. In my present invention the fusible element is not mounted to extend between the ferrules within the member 13 as in expulsion fuses previously provided, an example of which is illustrated and described in my co-pending application, Serial No. 333,315, filed January 18, 1929. In order to avoid the necessity of providing a fibre or other suitable fire resistant liner extending between the ferrules within the member 13 to protect it and the ferrules 15 from destruction due to the intense heat of the arc, as has been the practice heretofore, the objection to the provision of a liner being that it absorbs moisture to a certain extent and forms a high resistance electrical leak between the ferrules so that even after the fuse is blown, the circuit is still closed through the high resistance leak provided by the charred liner. In my present fuse support, I provide means for supporting the fusible link between the ferrules outside of the support and eliminate the liner between the ferrules to thus overcome the disadvantages aforesaid. This construction permits me to provide an expulsion means comprising an explosion chamber supported by one ferrule and having an outlet point downwardly away from the support member so as to direct the arc substantially away from the other ferrule which is never subjected to the damaging effects of the arc and hence the fire resistance lining heretofore employed may be entirely dispensed with or at most diminished in length to terminate far short of the remote ferrule to provide a rudimentary barrel extending from the explosion chamber solely for the purpose of giving direction to the expulsion of the arc and not necessarily to protect the ferrules or the spacing insulating tube 13. By thus eliminating the elongated liner, I reduce expense since the liners used in the devices heretofore provided have ever been a source of trouble and expense as pointed out in my co-pending application aforesaid.

In the device of my present invention, means is provided for electrically connecting the opposed ends of a fuse link 69 to the spaced caps 15, the fuse wire, however, extending between the caps outside of the member 13 so that when the fuse operates, the expulsion will not pass out through the

member 13 or either of the ferrules. The discharge takes place outside of the ferrules whereby the possibility of permanently creating an arc between the ferrules is substantially eliminated. The construction also eliminates the possibility of creating a high resistance leak between the ferrules after the fuse is blown.

To accomplish the foregoing result, one ferrule or cap 15 is provided with an expulsion device comprising an off-set portion 27, which may be conveniently formed integral with the ferrule. The off-set portion comprises a cylindrical member provided with a longitudinal bore, the axis of which forms an angle with the longitudinal axis of the spacing member 13 and the caps 15. The bore provides a substantially wide open mouth 31 at the lower end of the portion 27. The mouth is threaded internally to a substantial depth in order to threadingly receive the threaded end of a tubular member 43, which is or may be formed of bakelite, horn fibre, porcelain or other suitable heat resisting material. The bore of the cylindrical portion 27 extends inwardly of the threaded portion, being preferably restricted sufficiently to form a continuation of the bore of the tube 43 and to provide an explosion chamber 37. The bore of the portion 27 is restricted behind the explosion chamber 37 and opens onto the upper end of the off-set portion as a relatively small opening 39 sufficiently large to permit the fuse link to be inserted therethrough.

The other ferrule 15 is provided with an outwardly extending boss 29 having a central threaded stud 31, extending outwardly thereof and carrying a thumb nut 33, whereby one end of the fuse wire 69 may be electrically connected to the ferrule.

The upper end of the cylindrical portion 27 is preferably restricted and is externally threaded at 35 to receive a cap 51 provided to seal the opening 39 into the explosion chamber 37 and to secure the upper end of the fuse wire to the portion 27.

The fuse 69 preferably consists of a wire which may be formed of any well known or suitable fusible material such for instance as aluminum, zinc or copper, either pure or alloyed, with other materials. Of course other or special fuse links may be employed. The wire at its upper end is formed to provide an outwardly extending stop 45, whereby when the fuse is introduced through the restricted opening 39 in the upper end of the portion 27, this outwardly extending stop will lie upon the top of the threaded portion 33 as shown in the drawing. The stop 45 may be conveniently formed by curling the end of the fuse wire annularly in a plane perpendicular to the remaining portions of the wire. The lower portions of the fuse wire from a point spaced below the

upper curled end thereof may be plaited or otherwise coiled with a second length of wire in order to insure that the initial fusion of the link will occur in the upper portions, 5 that is, substantially in the explosion chamber 37 when the fuse is arranged in position in the fuse holder.

The fuse may be arranged in the fuse holder by removing the cap 41 and inserting 10 the lower end of the fuse wire through the opening 39 and passing the same downwardly through the explosion chamber 37 and tube 43 until the upper curled end of the fuse wire engages the top of the portion 15 33. The cap 51 may then be threaded upon the portion 33 to secure the upper end of the fuse wire firmly against the top of the housing 27, and in order to seal the opening 39 so that the force of the explosion caused 20 by the burning of the fuse wire in the chamber 37, will be directed downwardly through the tube 43 to thus expel the remaining unburned portions of the fuse link 69. The fuse link 69 is sufficiently long to extend out 25 through the open end of the tubular member 43 and the free plaited end of the fuse link 69 is finally secured to the remote ferrule by means of the thumb nut 33 so as to electrically connect the spaced ferrules by 30 means of the fuse link 69.

It will be noted that the tubular member 43 extends diagonally outwardly from the ferrule 15 at an angle with the axis of the elongated support comprising the member 33 and the spaced caps 15, so that the force 35 of the explosion is directed substantially away from the other cap 15. The portion 27, which contains the explosion chamber and which, therefore, will be subjected to considerable recoil reaction when the fuse 40 blows, is firmly supported from the fuse clips, not only because the ferrule on which it is mounted is firmly held between the arms of the clip, but also because it is mechanically connected to the remote ferrule 45 and fuse clips, so that the force of the explosion and expulsion is carried in part by both clips. In other words, the explosion housing is supported in part by both of the spaced fuse supporting clips to the end that 50 the entire assembly is firmly secured in operative position, whereby to reduce the possibility of dislodgment of the explosion housing during the discharge of the fuse.

55 My present invention entails the arrangement of the arc expelling devices in position to expell the arc in a direction which does not co-incide with the axis of the support member and so it is all the more necessary to preserve the strength and rigidity of the mounting.

It is thought that the other advantages of the explosion fuse of my invention, including the simplicity of construction and also the 60 fact that the fuse assembly may be mounted

in standard fuse supports, will be clearly understood from the foregoing description and it is obvious that numerous changes may be made in the form construction and arrangement of the several parts without departing from the spirit or scope of my present invention or sacrificing any of its attendant advantages, the form hereinbefore described being a preferred embodiment for the purpose of illustrating my invention. 70 75

Having thus described my invention, what I claim as new and desire to secure by Letters Patent is:

1. A fuse support comprising an elongated support member, including two spaced apart 80 members, insulating means between said members for maintaining their spaced relationship, said members being formed for connection to fuse support mounting elements, one of said members being formed with an 85 explosion chamber opening at an angle with the axis of said support, said members being formed to connect with a fuse link through said opening.

2. A fuse support comprising an elongated 90 member adapted for insertion between fuse support mounting elements, said elongated member having spaced ferrules and means for insulating and maintaining said ferrules in spaced relationship, one of said ferrules 95 having means forming an off-set explosion chamber, means for connecting a fuse link in said explosion chamber and means for connecting a remote portion of said fuse link to said other ferrule. 100

3. A fuse support comprising an elongated member providing spaced insulated terminals to which a fuse may be attached, one of said terminals having an integral off-set portion forming an explosion housing, opening 105 in a direction other than directly toward the other terminal, and means to connect remote portions of a fusible member electrically to said spaced terminals with a portion of the fusible member extending in said explosion housing, whereby the explosion housing is supported at all times from both terminals and whereby after the link is fused, there is 110 no electrical connection whatever between the terminals. 115

4. A fuse support comprising an elongated member having insulated and spaced apart ferrules at least one of which is adapted for detachable engagement in a fuse support mounting and an off-set explosion housing 120 carried by one of the ferrules in position such that the opening of the explosion housing extends at an angle with the longitudinal axis of the elongated member, said explosion housing comprising a portion provided with a longitudinal bore internally threaded at the mouth thereof, a tube of fire resistant material threaded into said bore, said bore being extended behind the inner end of said tubular member to form an explosion chamber and 125 130

being continued behind the explosion chamber as a restricted opening at the opposite end of the explosion housing, said opposite end of the housing being threaded to receive a cap 5 for sealing the restricted opening whereby a fuse link may be inserted through the restricted opening and clamped at one end by and between the cap and the threaded end of the explosion housing to extend thence 10 through the explosion chamber and then through the tubular member, and means in said other ferrule being provided with means for making an electrical connection with a remote portion of the fuse link, said tubular member being terminated short of said remote portion.

5. A fuse support comprising means forming an explosion housing and supporting means to support said housing from spaced 20 apart fuse clips, said supporting means comprising spaced ferrules at least one of which is adapted for detachable connection to spaced fuse support mounting elements and means for supporting the ferrules in spaced relation- 25 ship, said explosion housing forming an explosion chamber having an opening and being carried by one of said ferrules so that the opening extends at an angle with the axis of said ferrules, said explosion housing ter- 30 minating short of said other ferrule, means to connect a fusible link to said other ferrule whereby the link may extend from said ferrule through the opening of said explosion housing through said explosion chamber and 35 means to connect a remote portion of said link to said explosion housing in the bottom thereof.

6. A fuse support comprising an elongated member having spaced portions adapted for 40 connection to fuse support mounting elements, one of said portions having means forming an explosion chamber opening at the side of the member in a direction pointing substantially away from the other portion and means 45 for connecting a fusible member between said portions to extend through said opening.

7. The combination with fuse clips of a fuse holder comprising an elongated member having spaced portions adapted for connection 50 to fuse support mounting elements, one of said portions having means forming an explosion chamber opening at the side of the member in a direction pointing substantially away from the other portion, and a fusible 55 link mounted between said portions and having a portion extending in said chamber and through said chamber opening, said fusible link having means to insure fusion at the portion extending in the chamber whereby the 60 arc set up will expell itself and the remainder of the link outwardly of the elongated member.

8. The combination with fuse support 65 mounting elements of a fuse holder comprising an elongated member having spaced por-

tions adapted for connection to fuse support mounting elements, one of said portions having means forming an explosion chamber opening at the side of the member in a direction pointing substantially away from the 70 other portion and a fusible link having spaced portions detachably connected to said spaced portions and extending through said chamber and out through said opening.

9. An electric fuse comprising an elongated 75 member of insulating material, metallic members formed to fit fuse support mounting elements secured to the ends of the elongated member, one of said metallic members being formed with a housing opening at the side of the member and a fuse element connected to the said member and extending in said housing and out through the opening thereof, said element extending outside of said elongated member to the other metallic member. 80

10. An electric fuse comprising an elongated member of insulating material, metallic members formed to fit fuse support mounting elements secured to the ends of the elongated member, one of said metallic members being 85 formed with a housing opening at the side of the member and a fuse element detachably connected to the said member and extending in said housing and out through the opening thereof, said element extending outside of 90 said elongated member to the other metallic member and means to detachably connect the fuse element to said other member.

In witness whereof, I have hereunto subscribed my name.
